COMBINED CHECK-OUT COUNTER AND CANOPY THEREFOR

Thomas Charles Abrahamsen, Birmingham, Mich., and
John Dino Zaccai, Arlington, Mass., assignors to RCA
Corporation

Filed Apr. 20, 1972, Ser. No. 246,120

Term of patent 14 years

Int. Cl. D6—06

U.S. Cl. D6—143

Fig. 1.

Fig. 2.

Fig. 3.

Fig. 4.

Fig. 5.

Fig. 6.

Fig. 7.

FIG. 1 is a front perspective view of a combined check-out counter and canopy therefor showing our new design;

FIG. 2 is a front perspective view thereof, showing the canopy removed for ease of illustration;

FIG. 3 is a top plan view thereof;

FIG. 4 is a front elevational view thereof;

FIG. 5 is a rear elevational view thereof;

FIG. 6 is a left end elevational view thereof; and

FIG. 7 is a right end elevational view thereof.

We claim:

The ornamental design for a combined check-out counter and canopy therefor, substantially as shown and described.
